FLUTING ATTACHMENT FOR IRONS

Clara L. Kelley, Chicago, Ill.

Application November 14, 1946, Serial No. 709,717

4 Claims. (Cl. 223—36)

1

This invention relates to a fluting attachment for electric irons.

It is often desired to put ruffles or flutes in dresses or curtains.

In the past special fluting irons have been constructed for this purpose, which have been provided with cooperating fluting elements between which a piece of material may be disposed. Such fluting irons were heated on a stove before using.

No such fluting irons, to my knowledge, have been provided with electric heating elements, due largely to the price. A fluting iron would be used only occasionally by the ordinary housewife, and an electric fluting iron would be expected to carry a price considerably higher than the ordinary electric flatiron.

It is an object of my invention to provide a fluting device comprising a pair of cooperating fluting elements which are adapted to be heated by an ordinary electric flat iron.

A further object is to provide a fluting device of improved light weight structure, and of inexpensive construction.

A still further object is to provide a fluting device which can be used as an attachment for an ordinary electric flatiron, and which can be used in connection with electric irons of varying sizes and shapes.

Other objects, features and advantages of my invention will become apparent as this description proceeds.

Fig. 1 is a plan view of a preferred embodiment of my invention, a portion of the upper fluting element being broken away;

Fig. 2 is an elevation of Fig. 1, but also showing an electric iron secured to the fluting attachment, the dotted lines showing a changed position of the parts; and

Fig. 3 is an enlarged view taken along line 3—3 of Fig. 1, a portion of the upper fluting element being shown in displaced position to better show the construction thereof.

As indicated in Fig. 2, the reference numeral 10 indicates the fluting attachment generally, and the reference numeral 11 indicates an electric iron of a standard type. The fluting attachment comprises an upper element 12 and a lower element 13, which are hinged together by a hinge pin 14. The upper element is formed of a flat sheet of metal 15 and a corrugated sheet of metal 16, which are welded to each other along the ridges of the corrugations as indicated by the reference numeral 17. The flat sheet 15 is provided with a rearward extension 18 which has downwardly bent ears 19, forming a part of the hinge structure.

Similarly the lower element comprises a flat sheet 20 and a corrugated sheet 21 which are welded to each other as indicated by the reference numeral 22. The flat sheet 20 has a rearwardly

2

extending portion 23 having upwardly bent ears 24. The hinge pin 14 passes through ears 19 and 24.

Both of the upper and lower elements 13 and 14 are pointed and conform generally to the configuration of the ordinary electric flatiron, except that they are somewhat wider. On the upper surface of the sheet 15 is disposed a sheet of metal 25 which is shaped so as to form a recess to receive and grip the point of the iron 11. This sheet of metal is provided with flanges 26 which are welded to the flat sheet 15. Along the side marginal portions of the upper element 12 are provided two series of apertures 27, one at each side. The iron 11 is held in place on the upper element with its point projecting into the recess provided by the bent metal piece 25, by means of a coil spring 28, the ends of which terminate in hooks 29 for engagement with one or the other of the apertures of each of the series 27. Thus, the iron is securely held in place with its heated surface in contact with the flat sheet 15. The spring 28, and the selection of apertures provided permit electric flat irons of varying size and shape to be securely held in position.

In operation, after the iron is secured to the upper element, and has been sufficiently heated, the handle 30 of the iron is grasped and the iron is tilted upwardly and backwardly. Thus, the elements 12 and 13 are separated, the upper element being hingedly mounted on the lower element as pointed out above. A piece of fabric is then inserted between the elements and the iron permitted to close so that the parts are in operative position. The heat of the iron is transmitted to the corrugated sheets 16 and 21, both by conduction through the welded joints 17, and by radiation from the lower surface of the flat sheet 15 to the upper surface of the corrugated sheet 16. It has been found that this arrangement provides the transmission of sufficient heat to achieve the desired fluting. The parts need be maintained in their operating position only momentarily, and then the iron again raised and the fabric withdrawn. The dotted line position, as shown in Fig. 2, indicates the pivotal movement of the iron and the upper element 12 with respect to the lower element 13. The dotted line position is an extreme position, in which the iron may be raised in the event that both of the operator's hands are occupied with arranging the fabric above the corrugations of the lower element 13. In other instances, when one hand is sufficient to feed the fabric, the iron need be lifted less than thirty degrees.

It will be observed that the extensions 18 and 23 provide an arrangement by which the hinge pin is offset from the back edges of the corrugated strips 16 and 21 by a considerable distance. This arrangement reduces the angle through which the

iron and the upper element 12 need be lifted in order to utilize the full area of the corrugated sheets 12 and 21.

Although only a preferred embodiment of my invention has been shown and described herein, it is obvious that various modifications and changes may be made in the construction shown without departing from the spirit of my invention as defined in the appended claims.

I claim:

1. A fluting device for use with an electric flatiron comprising a pair of cooperating fluting elements, each fluting element comprising a flat piece of sheet metal and a corrugated piece of sheet metal, the ridges of the corrugations of said corrugated piece of sheet metal being secured to said flat sheet of metal in heat transmitting relationship, and means for hingedly securing said fluting elements to each other so that the corrugations of one of said fluting elements will fit into the corrugations of the other, as the two are moved into cooperating relationship.

2. A fluting attachment for an electric flatiron comprising a pair of cooperating fluting elements, each fluting element comprising a flat piece of sheet metal and a corrugated piece of sheet metal welded to each other along their contacting portions, said flat sheet having a rearwardly extending portion with bent over ears, said cooperating fluting elements being arranged one above the other with the bent over ears of each in juxtaposition with the bent over ears of the other, and a hinge pin passing through said bent over ears.

3. A fluting attachment for an electric flatiron comprising a pair of cooperating fluting elements hinged to each other, each fluting element comprising a flat piece of sheet metal and a corrugated piece of sheet metal secured to each other along the ridges of said corrugations, the front portion of the upper surface of the upper one of

said fluting elements being provided with means to receive the point of an electric flatiron, two series of apertures arranged along the side marginal portions of said upper fluting element, and resilient binding means removably interlocking with one or the other of the apertures in each series in order to maintain an electric flatiron in position on the upper surface of said upper fluting element, with the point of the iron received within said recess forming means.

4. A fluting attachment for an electric flatiron comprising a pair of cooperating fluting elements, each fluting element comprising a flat piece of sheet metal and a corrugated piece of sheet metal welded to each other along their contacting portions, said flat sheet having a rearwardly extending portion with bent over ears, said cooperating fluting elements being arranged one above the other with the bent over ears of each in juxtaposition with the bent over ears of the other, and a hinge pin passing through said bent over ears, the front portion of the upper surface of the upper one of said fluting elements being provided with means to receive the point of an electric flatiron, an aperture provided along each side marginal portion of said upper fluting element, and a coil spring removably interlocking at either end with said apertures in order to maintain an electric flatiron in position on the upper surface of said upper fluting element, with the point of the iron received within said recess forming means.
